UNITED STATES PATENT OFFICE.

WILLIAM McCONWAY, JR., OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

DRAFT APPLIANCE FOR RAILWAY-VEHICLES.

1,362,022.

Specification of Letters Patent. Patented Dec. 14, 1920.

Application filed June 12, 1919. Serial No. 303,694.

To all whom it may concern:

Be it known that I, WILLIAM McCONWAY, Jr., a citizen of the United States, residing at Pittsburgh, in the county of Allegheny and State of Pennsylvania, have invented certain new and useful Improvements in Draft Appliances for Railway-Vehicles; and I do hereby declare the following to be a full, clear, and exact description of the invention, such as will enable others skilled in the art to which it appertains to make and use the same.

My invention relates to the construction and mode of manufacture of draft rigging or draft appliances for railway cars, and has for its object to provide for the attachment of the coupler and yoke or equivalent draft members in a manner promoting great simplicity, strength and compactness of structure and the elimination of maintenance costs such as are attendant upon the use of tail pins, nuts, cotters, keys and blocks commonly employed in the connection of couplers to their draft yokes. Generally stated, this object is accomplished by casting the coupler and yoke in conjoined relation so that a portion of one of the members clasps or embraces a portion of the other to form an inseparable jointed connection. In practice it is preferred to cast the yoke and coupler dissimultaneously, first finishing one and then casting the other in interlocked relation thereto, and a method of thus manufacturing the device is illustrated in the drawings and will hereinafter be described; but it is to be understood that I do not limit myself to any particular method of casting the parts.

In the drawings illustrating the preferred form of my invention, the scope whereof is pointed out in the claims,

Figure 1 is a plan view of a coupler and draft yoke constructed in accordance with my invention, a portion of the forward end of the yoke being broken away to disclose the rear end of the coupler stem and the coupler receiving recess or socket at the forward end of the yoke.

Fig. 2 is a view, partly in side elevation

and partly in vertical central section, of the construction shown in Fig. 1.

Fig. 3 is an elevational view of the forward end of the draft yoke.

Fig. 4 is a detail horizontal section of the forward end of the yoke, showing in plan a centrally disposed block or form used for shaping the cores at the sides of the yoke.

Fig. 5 is a detail vertical section of the devices illustrated in Fig. 4, the core shaping form being in side elevation.

Fig. 6 is a detail horizontal section of the forward end of the yoke with its side cores, the core shaping form having been removed.

Fig. 7 is a detail vertical section of the construction shown in Fig. 6.

Fig. 8 is a vertical central section of the rear portion of the mold with cores set ready for pouring the coupler.

Fig. 9 is a plan view of the portion of the mold shown in Fig. 8, parts being broken away for the purpose of more clearly exhibiting the relations of the cores and yoke.

Fig. 10 is a plan view of the rear end of the coupler pattern.

Fig. 11 is a side elevation of the portion of the pattern illustrated in Fig. 10.

Fig. 12 is a detail perspective view of cores for use exteriorly of the yoke at the forward end thereof.

Fig. 13 is a detail perspective view of cores employed in forming the coupler, the forward portion of the main core being omitted.

In the drawings, 1 is the coupler and 2 is the draft yoke. The head 3 of the coupler may be of any usual or desired design, as also may be the rear portion of the yoke. It is preferred, however, as shown, to form the rear part of the yoke with parallel arms 4 which are integrally connected at opposite ends by transverse bars or walls, 5 and 6 respectively, the forward bar 5 being adapted to engage the forward follower or end of a cushioning unit (not shown) and the rear wall or bar 6 being adapted to engage the rear follower or end of the cushioning unit.

The coupler 1 is inseparably but movably

interlocked with the yoke 2, the rear end or butt of the coupler stem being for that purpose provided on opposite sides with integrally united projections preferably formed as axially aligned cylindrical trunnions 7 constituting a pivotal connection allowing the coupler to swing laterally with respect to the yoke. The forward end of the yoke, which is preferably of hooded form having 10 outwardly divergent side walls 8 affording opportunity for the coupler to swing, is provided with locking shoulders 9 that extend in front of and overlappingly engage the corresponding trunnions 7. These shoulders 9, whose inner faces are preferably curved to conform to the trunnions on the coupler, are integrally and inseparably united through the side walls 8 of the yoke and hence permanently maintain the coupler in interlocked relation with the yoke.

The forward face of the transverse bar 5 connecting the arms 4 of the yoke is preferably curved to afford an extended bearing 10 for the trunnions 7 during a buffing movement of the coupler. When the bar or wall 5 is employed the coupler will be prevented from moving rearwardly with respect to the yoke, and it will be readily understood by those skilled in the railway draft appliance art that this special detail of the preferred construction is inapplicable to the type of draft rigging in which the yoke remains stationary when the coupler is forced rearwardly. The curved bearing surface of 30 the locking shoulders 9 form cylindrical pockets on opposite sides of the longitudinal axis of the yoke conforming to and receiving the respective trunnions 7 of the coupler.

Between the curved interior surface 10 and the respective side walls 8 the yoke is preferably provided with shoulders 11, since such a construction facilitates the making of the cores which are formed within the hooded end of the yoke at the sides thereof 45 preliminary to casting the coupler in conjoined relation to the yoke. As a means for positioning and sustaining the cores for the coupler, the upper and lower walls of the yoke are preferably formed with aligned 50 openings 12 and the wall or tie bar 5 is preferably provided with a centrally disposed opening 13, these several openings being adapted to receive the ends of certain of the cores employed.

55 In producing the device it is preferred to cast the coupler and yoke dissimultaneously, the yoke preferably being cast first. In following the preferred procedure the yoke 2 is cast and cleaned and cores are 60 then applied adjacent the side walls 8 of the yoke, as shown at 14. These cores may be formed conveniently by inserting in the front end of the yoke a form or core shaping block 15, as shown in Figs. 4 and 5, ramming sand between the shaping block 15 and the

side walls 8 of the yoke, and thereafter removing the block, thus leaving the sand in place in the yoke as shown in Figs. 6 and 7. A coupler mold having been prepared from the coupler pattern 16 (see Figs. 10 and 11), 70 the yoke 2 with the cores 14 in place is lowered into the drag or lower part 17 of the mold into which it neatly fits. The cores 18, 19, 20 and 21 are then set, sand is packed in the opening in the yoke for receiving the 75 cushioning unit, as indicated at 22 (see Fig. 8), and also at the sides of the yokes to the rear of the cores 19, as indicated at 23. The cope 24 of upper half of the mold is then lowered into position for pouring, which 80 may be done through an opening 25 conveniently located in the mold.

Core 18, which is provided with a central recess 26 of sufficient dimensions to receive the main core 20 of the coupler and allow 85 for the formation of the walls of the shank of the coupler 1 between those cores, abuts the forward end of the yoke 2, occupying the space in the mold provided by the bevel or draft 28 on the upper part of the rear 90 portion of the pattern 16. The cores 19, which contact the side walls 8 of the forward end of the yoke and abut against the rear face of the core 18, also occupy the space in the mold formed by the bevel 28 of the coupler pattern. The rear end of the main coupler core 20 is preferably provided with a portion 27 which extends into the opening 13 in the transverse wall 5 of the yoke, thus supporting and insuring proper positioning 100 of the core. The cores 21, which abut the main coupler core 20 at their inner ends, extend into the openings 12 of the yoke and thus are maintained in position.

The cores 19 with the sand packed in their 105 rear give stability to the core 18 and to the yoke 2. The comparatively great bevel or draft 28 on the coupler pattern imparts a form to the sand in the cope 24 preventing its displacement when the cope is being lowered into position for pouring.

I claim:

1. A railway draft appliance comprised of a plurality of metal members capable of relative pivotal movement, said members 115 being inseparably connected by casting and being provided with interlocking parts integral with said members, one of said members being provided with means for positioning a core during the casting of the adjacent one of said members.

2. A railway draft appliance comprised of a plurality of cast metal members capable of relative pivotal movement, said members being inseparably connected by interlocking 125 parts constituting cored trunnions and trunnion sockets, one of said members being provided with means for positioning a trunnion core in the trunnion sockets during the casting of said trunnions.

3. A railway draft appliance comprised of a cored coupler member and a yoke member, both of said members being of cast metal and being inseparably connected by 5 interlocking parts integral with said members, the coupler member being cast in operative relation with the yoke member, and the yoke member being provided with means for positioning a coupler core in proper relation to the yoke member during the casting of said coupler member.
- In testimony whereof I affix my signature.

WILLIAM McCONWAY, JR.
